UNITED STATES PATENT OFFICE.

EMIL J. F. QUIRIN, OF TIOGA CENTER, NEW YORK.

LEATHER-STAKING MACHINE.

1,036,335.

Specification of Letters Patent. Patented Aug. 20, 1912.

Application filed January 2, 1912. Serial No. 669,086.

To all whom it may concern:

Be it known that I, EMIL J. F. QUIRIN, a citizen of the United States, resident of Tioga Center, in the county of Tioga and State of New York, have made a certain new and useful Invention in Leather-Staking Machines; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a side view of my machine with the adjusted portion of the parts shown in dotted lines. Fig. 2 is a plan view of the invention.

The invention has relation to leather staking machines for stretching and softening leather, and is designed to provide a practical and efficient machine operating upon a rotary principle.

The invention consists in the novel construction and combinations of parts, as hereinafter set forth.

In the accompanying drawings, illustrating the invention, the numeral 1 designates the supporting frame of the machine, carrying at its upper forward end a rotary shaft 2, and above and somewhat in rear of the same a second rotary shaft 3. The lower rotary shaft 2 is provided with a wheel 4, carrying a plurality of radial-staking blades 5, of steel or other suitable material, said blades in the rotation of the wheel projecting through a slot 6 in a platform or table 7.

The upper shaft 3 carries a wheel 8 having at the free ends of radial arms 9 thereof, a plurality of staking rollers 10, similar in number to and located within the intervals 11 between the staking blades, said rollers being covered with felt or other suitable material. The front edge of the leather being worked may be held by the workman's hands or by his chest against the forward edge of the table at 12, and as the two wheels are rotated, a lever, preferably a treadle lever, 13 is operated to press each blade against its roller to a degree depending upon the pressure exerted upon the treadle, by means hereinafter described.

Means are provided for rotating the upper shaft and its roller-carrying wheel, consisting preferably of wheels or cranks 14 at each side of the machine and connecting

rods 15, the rear wheels or cranks being located upon a power shaft 16 having tight and loose pulleys 17; and means are provided for rotating the lower shaft and its 60 blade-carrying wheel, consisting preferably of a chain 18 passing over a sprocket 19 upon the shaft 2, and over sprocket 20 carried by a shaft 21 at the rear end of the machine, just below the power shaft, with 65 which it has a gear connection at 22.

The pressure-applying means referred to consists preferably of a roller 23, at one end of a crank arm 24, upon the treadle shaft 25, said roller in the operation of the lever or 70 treadle pressing down upon the chain and causing the blade-carrying wheel to turn toward the roller-carrying wheel, to impart the necessary pressure. At the same time, means are provided in connection with the 75 pressure wheel to exert a tension upon the chain and insure that it is tight, for a proper operation of the pressure wheel this means consisting preferably of a roller 26, at the end of an arm 27, said arm having a rod 28, 80 slidably engaging a perforation 29, thereof and provided with a spring 30, surrounding the same and bearing at one end against said arm and at its other end against a collar 31, of said rod, which is connected at its lower 85 end to the frame at 31. The roller 26, is in contact with the inner face of the lower half of the chain, and as the pressure is applied upon the chain for the purpose stated, the roller 26, will rise against the tension of 90 the spring, and be returned to normal position by the spring when the pressure is released.

My rotary machine is of simple, durable and compact nature, capable of being easily 95 operated, and will effectually perform the functions for which it is intended.

Having thus described my invention, what I claim as new and desire to secure by Letters Patent is:

1. In a leather staking machine, a bearing against which the leather is designed to be pressed at one end to retain it in position, and rotary means for simultaneously scraping and stretching the leather, including a 105 wheel having a plurality of staking blades projecting therefrom at intervals, and a second wheel carrying a plurality of staking rollers, said rollers and said blades having intermeshing engagement with each other. 110

2. In a leather staking machine, a bearing against which the leather is designed to be

pressed at one end to retain it in position, and rotary means for simultaneously scraping and stretching the leather, including a wheel having a plurality of staking blades 5 projecting therefrom at intervals, and a second wheel carrying a plurality of staking rollers, said rollers and said blades having intermeshing engagement with each other, a positive crank drive for said second wheel, 10 and a chain drive for the blade-carrying wheel, and means acting upon said chain to press a roller and a blade together.

3. In a leather staking machine, a bearing 15 against which the leather is designed to be pressed at one end to retain it in position, and rotary means for simultaneously scraping and stretching the leather, including a wheel having a plurality of staking blades projecting therefrom at intervals, and a second 20 wheel carrying a plurality of staking rollers, said rollers and said blades having intermeshing engagement with each other, a positive crank drive for said second wheel, and a chain drive for the blade-carrying 25 wheel, and means acting upon said chain to press a roller and a blade together, including a guide roller in the path of the chain to cause it to take a crooked path, lever operated means for pressing down on said guide 30 roller and the upper half of the chain, and a tension device for said chain.

4. In a rotary leather staking machine, a wheel, a plurality of staking blades having projection from said wheel at regular intervals, a second wheel, a plurality of rollers carried by and located at regular intervals upon said second wheel, said rollers and said 35 blades having intermeshing engagement with each other, means for rotating the two 40 wheels at the same rate of speed, and lever operated means for pressing the rollers and the blades together.

5. In a rotary leather staking machine, a

wheel, a plurality of staking blades having projection from said wheel at regular intervals, a second wheel, a plurality of rollers carried by and located at regular intervals upon said second wheel, said rollers and said 45 blades having intermeshing engagement with each other, means for rotating the two 50 wheels at the same rate of speed, and lever operated means for turning the blade-carrying wheel to press the rollers and the blades together.

6. In a rotary leather staking machine, a 55 wheel, a plurality of staking blades having projection from said wheel at regular intervals, a second wheel, a plurality of rollers carried by and located at regular intervals upon said second wheel, said rollers and said 60 blades having intermeshing engagement with each other, means for rotating the two 65 wheels at the same rate of speed, including a chain and sprocket gearing, and lever operated means for exerting pressure upon said chain to press the rollers and the blades together.

7. In a rotary leather staking machine, a 70 wheel, a plurality of staking blades having projection from said wheel at regular intervals, a second wheel, a plurality of rollers carried by and located at regular intervals upon said second wheel, said rollers and said 75 blades having intermeshing engagement with each other, means for rotating the two 80 wheels at the same rate of speed, including a chain and sprocket gearing, lever operated means for exerting pressure upon said chain to press the rollers and the blades together, and a tension device for said chain.

In testimony whereof I affix my signature, in presence of two witnesses.

EMIL J. F. QUIRIN.
